UNITED STATES PATENT OFFICE.

FRANKLIN L. BARBER AND EDWIN W. WEBB, OF CHICAGO, ILLINOIS, ASSIGNEES TO
STANDARD CAR TRUCK COMPANY, OF CHICAGO, ILLINOIS, A CORPORATION OF NEW
JERSEY.

SIDE BEARING FOR CARS.

1,310,556.

Specification of Letters Patent. Patented July 22, 1919.

Application filed December 9, 1918. Serial No. 265,830.

To all whom it may concern:

Be it known that we, FRANKLIN L. BARBER and EDWIN W. WEBB, citizens of the United States, residing at Chicago, in the county of Cook and State of Illinois, have invented certain new and useful Improvements in Side Bearings for Cars; and we do hereby declare the following to be a full, clear, and exact description of the invention, such as will enable others skilled in the art to which it appertains to make and use the same.

Our invention has for its object to provide an improved anti-friction side bearing for railway cars; and, to this end, it consists of the novel devices and combinations of devices hereinafter described and defined in the claims.

In the accompanying drawings, which illustrate the invention, like characters indicate like parts throughout the several views.

Referring to the drawings,

Figure 1 is a plan view of the invention with some parts broken away and some parts sectioned;

Fig. 2 is a view partly in longitudinal central section and partly in elevation;

Fig. 3 is an end elevation;

Fig. 4 is a view principally in transverse vertical section; and

Fig. 5 is a view corresponding to Fig. 2, with the exception that the parts are moved in one of their extreme positions.

The numerals 6 and 7 indicate, respectively, the body bolster and the truck bolster of a railway car.

The improved anti-friction side bearing, as shown, is carried by the body bolster 6 and includes a cast rectangular housing 8 with an open top and bottom. Cast with the upper portion of the housing 8, at the corners thereof, are four horizontally disposed ears 9 having bores 10, through which are passed to rigidly secure the side bearing to the body bolster 6. The top surfaces of the housing 8 and ears 9 extend in an oblique plane to conform to the surface of the body bolster to which they are secured and have flat engagement therewith.

On the end walls of the housing 8, are inwardly projecting horizontal flanges or shoulders 11 on which is loosely supported

a wearing plate 12, that completely closes the open top of the housing and is held thereby against horizontal movement.

A cast cover 13, for the housing 8, rests directly upon the wearing plate 12 and its upper surface extends in the same oblique plane as the upper surfaces of the housing 8 and ears 9, so as to bear directly against the body bolster 6. The top of the cover 13 is cored, for the sake of lightness and saving of material. The ends of the cover 13 terminate short of the respective ends of the housing 8, and cast therewith, at the bottom thereof, are small flanges 14, provided for a purpose that will presently appear.

The inner faces of the sides of the housing 8 are recessed and, on the lower horizontal side flanges thereof, is formed a pair of opposite wheel seats 15. These wheel seats 15, from their longitudinal centers, have upwardly diverging contours, at the outer ends of which are wheel stops 16.

The body bolster 6 and load carried thereby are supported from the truck bolster 7 by a rocker 17, as shown, in the form of a wide faced ring-like roller, with just enough end clearance to work freely within the housing 8. Normally the roller 17 rests on a wearing plate 18 secured to the truck bolster 7 and the wearing plate 12 rests on the uppermost face of said roller and supports the load directly through the cover 13, which is entirely free from the housing 8.

A heavy carrier pin 19 is inserted axially through the ring-like roller 17 and has loosely journaled on its ends, with freedom for slight radial movement in respect thereto, a pair of wheels 20. These wheels 20 rest on the seats 15, are normally self-centered thereby and support the carrier pin 19 therefrom. When the load is supported from the truck bolster by the roller 17, said roller is out of contact with the pin 19 and, as long as the weight of the car body continues on the roller, the motion is simple and said roller moves back and forth on the wearing plates.

In case the car body lifts, with respect to the car truck, the carrier pin 19 picks up the roller 17 and lifts the same out of contact with the wearing plate 18, at which time the upper surface of said pin and the axial

opening in said roller become coöperating fulcrum surfaces, which are located above the center of gravity of the roller. If the truck is on a curve at the time the roller 17 is lifted from the wearing plate 18, said roller will swing with pendulum-like action on the carrier pin 19 and, at the same time, the wheels 20, which carry said pin being on the inclined surfaces of the wheel seats 15, will roll back to the center thereof and self-center themselves. This self-centering of the wheels 20, together with the added weight of the carrier pin 19 and pendulum-like action of the roller 17, will assist one another to return to normal position. It will thus be seen that the instant the roller 17 is lifted out of engagement with the wearing plate 18, the movable parts of the side bearing are immediately returned to normal position for engagement with wearing plate 18, when the car body again assumes its normal position.

Formed in the side walls of the housing 8, are two pairs of alined openings 21, through any one of which the carrier pin 19 may be inserted endwise to and from a position within the housing 8. The length of the carrier pin 19 is such as to snugly fit between the side walls of the housing 8, which hold the same against endwise movement. It will be noted that the axes of the openings 21 are located in an elevation sufficiently above the elevation of the normal position of the projected axis of the carrier pin 19, to prevent said pin from being accidentally displaced therethrough.

In assembling the improved anti-friction side bearing, the wheels 20 are first placed on the wheel seats 15 and then the roller 17 is placed in the housing 8 between the wheels 20. Next, the carier pin is inserted into one of the openings 21 and axially through, first, the adjacent wheel 20, then, the roller 17, and finally, the other wheel 20. A further axial movement of the carrier pin 17 will clear the respective opening 21 and allow the same to drop into the housing 8 to position the wheels 20 on the wheel seats 15. Next, the wearing plate 12 is placed on the flanges 11 and the cover 13 on said wearing plate. To hold the parts in assembled relation before the side bearing is secured to the body bolster, the upper edges of the end walls of the housing 8 are bent inward, as indicated by broken lines at 22 in Fig. 5, by pounding or otherwise, so as to overlie

the flanges 11 on the ends of the cover 13, and thereby hold said cover in the housing.

What we claim is:—

1. In an anti-friction side bearing, the combination with upper and lower bearing plates, of a housing secured in respect to the upper bearing plate and having self-centering wheel seats, an interposed rocker normally supporting the upper bearing plate from the lower bearing plate and having an axial opening, a carrier pin extending through the axial opening in the rocker, said rocker and carrier pin having normally separated fulcrum surfaces, the fulcrum surface of the rocker being located above the center of gravity thereof, and wheels supporting the carrier pin from the wheel seat. 60 70

2. In an anti-friction side bearing, the combination with upper and lower bearing plates, of a housing secured in respect to the upper bearing plate and having self-centering wheel seats, an interposed rocker normally supporting the upper bearing plate from the lower bearing plate and having an axial opening, a carrier pin extending through the axial opening in the rocker, said rocker and carrier pin having normally separated fulcrum surfaces, the fulcrum surface of the rocker being located above the center of gravity thereof, and wheels loosely journaled on the carrier pin and supporting the same from the wheel seats. 75 80

3. In an anti-friction side bearing, the combination with upper and lower bearing plates, of a housing secured in respect to the upper bearing plate and having self-centering wheel seats, an interposed rocker normally supporting the upper bearing plate from the lower bearing plate and having an axial opening, a carrier pin extending through the axial opening in the rocker, said rocker and carrier pin having normally separated fulcrum surfaces, the fulcrum surface of the rocker being located above the center of gravity thereof, and wheels loosely journaled on the carrier pin with freedom for limited radial movement with respect thereto and supporting said pin from the wheel seats. 90 95 100 105

In testimony whereof we affix our signatures in presence of two witnesses.

FRANKLIN L. BARBER
EDWIN W. WEBB.
